UNITED STATES PATENT OFFICE.

THOMAS J. CALLAHAN, OF DAYTON, OHIO, ASSIGNOR TO THE T. J. CALLAHAN COMPANY, OF DAYTON, OHIO, A CORPORATION OF OHIO.

OPERATING MECHANISM FOR VENTILATORS.

Application filed August 20, 1923. Serial No. 658,227.

To all whom it may concern:

Be it known that I, THOMAS J. CALLAHAN, a citizen of the United States, residing in the city of Dayton, in the county of Montgomery and State of Ohio, have invented certain new and useful Improvements in Operating Mechanism for Ventilators, of which the following is a specification.

It is the principal object of my invention 10 to provide for ventilators and like structures, an operating mechanism comprising a segmental rack and pinion construction which is adequately flanged and one in which friction is reduced to the minimum.

15 It is another object of my invention to provide flanges on the pinion which not only reinforce its teeth, but which tend to hold it, the rack and the yoke pieces in such upright relation to each other that side strains and attendant friction are materially reduced.

In the accompanying drawings, Figure 1 is a side elevational view of my double-flanged pinion operating mechanism applied to the ventilating sash of a building. 25 Figure 2 is a side elevational view of the double-flanged pinion between the yoke pieces and the segmental rack. Figure 3 is a cross sectional view taken through the same on the line 3—3 of Figure 2. And Figure 4 is a side elevational view of the pinion, partly broken away and in section to show how the teeth are reinforced by the flanges on it.

Throughout the specification and drawings, similar reference characters denote corresponding parts.

Referring to the accompanying drawings for a detailed description of my invention, the numeral 1 designates a roof to the beam 40 2 at the angle of which there is hingedly secured a ventilating sash 3. Secured to a rafter 4 is an arm 5 in the lower end of which a shaft 6 is suitably journaled and adapted to be rotated by a crank or other means not 45 shown. (See Figure 1.)

Fixedly secured to the shaft 6 by means of a screw bolt 7, is a sleeve pinion 8 which is preferably a casting formed like a hub, tapering at one end and having an annular 50 recess 9 formed in its outer periphery near its other end. (See Figure 3.) Projecting outwardly from the casting on each side of the recess 9 is an annular flange 10. Formed around, and integral with, the bottom of the 55 recess 9 between the annular flanges 10, 10,

are radial pinion teeth 11 which do not extend quite to the outer circumferential edges of the latter. By these flanges 10, 10 the teeth 11 are adequately reinforced for engagement with the teeth of a segmental rack 60 12 that is pivotally secured at its outer end to the ventilating sash 3.

Surrounding the hub of the pinion 8, one on each side of its double flanged portion, are the curved parts of two flat metal yoke 65 pieces 13, 13 which, beyond the flanges, taper inwardly to the plane of them, and then project outwardly in parallelism a sufficient distance to permit the rack 12 to move freely between them. At their free ends the two 70 yoke pieces are connected by pintles 14, 14 on which are mounted rollers 15, 15 respectively, which, when they are engaged by the upper curved surface of the rack, offer a minimum resistance to its longitudinal 75 movement. (See Figures 1, 2 and 3.) The lower curved portions of the yoke pieces are connected by a spacing pin 16.

When the construction is assembled, the annular flanges 10, 10 on the pinion 8 will 80 straddle the toothed portion of the segmental rack 12 with which its teeth 11 are in engagement, and will rotate freely between the curved portions of the yoke pieces 13, 13 whose outer ends also straddle the rack. The 85 pinion, therefore, by virtue of its double flanged hub, will serve to maintain the rack and yoke pieces in proper upright relation to it, not only to prevent it from jumping off the rack but also to minimize side strains 90 and reduce friction to the minimum. The flanges 10, 10 not only contribute to an easy and safe operation of the device, but they also serve to reinforce the pinion teeth for a strong engagement between them and the 95 teeth of the segmental rack. Since the hub, the flanges and the teeth of the pinion are made in one piece, the construction of the device is simplified without subtracting from the manifold advantages effected. 100

Having described my invention, I claim:

1. In a device of the type described, a pinion, a segmental rack in engagement with said pinion, a pair of yoke pieces whose curved ends surround said pinion and between whose outer ends said rack is longitudinally movable, restraining means between the outer ends of said yoke pieces for engagement by the rack, and a pair of annular flanges on the pinion, one on each side 110

of its teeth, to reinforce the latter and to straddle the teeth on the rack and freely rotate between the curved portions of the yoke pieces, for the purpose specified.

5. 2. In a device of the type described, a pinion having an elongated hub, said pinion having an annular recess in the outer periphery of its hub, an annular flange projecting outwardly from said hub on each 10 side of the annular recess therein, teeth formed integrally around the bottom of said recess between said flanges, a segmental rack in engagement with said teeth, a pair of yoke pieces whose curved ends surround

said pinion and between whose outer ends 15 the rack is longitudinally movable, and restraining means between the outer ends of said yoke pieces for engagement by the rack, the flanges on the pinion straddling the latter and freely rotatable between the 20 curved portions of the yoke pieces, for the purpose specified.

In testimony whereof I have hereunto set my hand this 17th day of August, 1923.

THOMAS J. CALLAHAN.

Witness:

HOWARD S. SMITH.
